FURNACE

Original Filed July 18, 1927

FIG. 5 *Lennel V. Reese*
INVENTOR.

BY *W. L. Lind*
ATTORNEYS.

UNITED STATES PATENT OFFICE

LEMUEL V. REESE, OF CINCINNATI, OHIO, ASSIGNOR TO ERIE CITY IRON WORKS, OF ERIE, PENNSYLVANIA, A CORPORATION OF PENNSYLVANIA

FURNACE

Application filed July 18, 1927, Serial No. 208,495. Renewed January 22, 1930.

- Furnaces have been provided with ignition chambers, or furnace extensions, into which fuel is introduced, particularly fine fuel such as powdered coal, or atomized oil.
- 5 The present invention is designed to improve the construction and operation of such ignition extensions. Features and details of the invention will appear from the specification and claims.
- 10 A preferable embodiment of the invention is illustrated in the accompanying drawings as follows:—
- Fig. 1 shows a central section of a portion of the furnace with the ignition chamber, or 15 extension thereon.
- Fig. 2 a section on the line 2—2 in Fig. 1.
- Fig. 3 an enlarged section of a portion of the wall showing the means of regulating the air supply.
- 20 Fig. 4 a section on the line 4—4 in Fig. 1.
- Fig. 5 an enlarged view of a portion of the frame of the extension.
- 1 marks the furnace having the front wall 2. A fuel delivery opening 3 extends through 25 the wall and the furnace extension or ignition chamber is arranged in front of the opening 3. The extension is provided with a refractory lining 4 which is made up of bricks formed in segments and this is supported by 30 a frame comprising I beams 5 extending fore and aft outside of the refractory lining, the joints of the refractory lining being preferably radially in line with the bars as clearly shown in Fig. 2. An outer shell 6 is arranged 35 around the bars 5 and secured thereto by means of bolts 7. Air passages 8 are formed between the shell 6 and the refractory lining 4 and these are separated by means of the beams 5. The passages are closed at the front 40 end of the extension by a flange 9 formed on the shell 6.
- The shell has a series of openings 10 at the rear end of the extension leading into passages 8. Bricks 11 are arranged around 45 the front end of the extension and these have openings 12 leading from the passages 8. Preferably the passages 12 extend at an angle to radial lines, or are more or less tangential. A ring 13 is rotatively mounted on the shell 50 6 over the openings 10 and it is provided with openings 14 which are adapted to be brought into and out of register with the openings 10 so as to regulate the inlet capacity of these openings to the passages 8. A handle 15 is provided for operating the 55 regulating ring.
- Fuel is delivered through the front wall of the extension by pipes 16 which, as shown, are adapted to deliver comminuted fuel with some air. The pipes lead from a supply pipe 60 17 and this in turn leads from an ordinary pulverizer (not shown).
- In the operation of the device, it will be noted that air, which would ordinarily be secondary air, is drawn in through the openings 65 14 and 10 and traverses the passages 8 along the refractory lining, thus cooling this lining and at the same time preheating the air. The air is then delivered into the furnace through the front end of the extension. By arranging 70 the frame with the bars fore and aft a passage of the air is obtained throughout the circumference of the casing so that equal cooling of the refractories is assured. This arrangement of the bars also simplifies the construction in that ordinary straight bars may 75 be used in forming the frame.
- What I claim as new is:—
1. In an apparatus of the class described the combination of a furnace chamber; an 80 ignition chamber having an annular wall and with an axially extending inlet and discharge, the discharge leading to the furnace chamber; means for delivering fuel axially into the inlet end of the ignition chamber; and a shell surrounding the ignition chamber and spaced therefrom, said shell having an 85 air inlet opening remote from the inlet end of the ignition chamber, and the annular wall of the chamber having air openings therethrough from the space to the ignition chamber at its inlet end, the space between the shell and wall permitting a longitudinal flow of air from the air inlet to the openings through the wall.
2. In an apparatus of the class described the combination of a furnace chamber; an 90 ignition chamber having an annular wall and with an axially extending inlet and discharge, the discharge leading to the furnace chamber; 95
- 50 6 over the openings 10 and it is provided
- 100

- ber; means for delivering fuel axially into the inlet end of the ignition chamber; and a shell surrounding the ignition chamber and spaced therefrom, said shell having an air inlet opening remote from the inlet end of the ignition chamber, and the annular wall of the chamber having tangentially directed air openings therethrough from the space to the ignition chamber at its inlet end, the space between the shell and wall permitting a longitudinal flow of air from the air inlet to the openings through the wall.
3. In an apparatus of the class described the combination of a furnace chamber; an ignition chamber having an annular wall and with an axially extending inlet and discharge, the discharge leading to the furnace chamber; means for delivering fuel axially into the inlet end of the ignition chamber; a shell surrounding the ignition chamber and spaced therefrom, said shell having an air inlet opening remote from the inlet end of the ignition chamber, and the annular wall of the chamber having air openings therethrough from the space to the ignition chamber at its inlet end, the space between the shell and wall permitting a longitudinal flow of air from the air inlet to the openings through the wall, and means for adjusting the area of the air opening to the shell.
4. In a furnace, the combination of a furnace chamber; a stationary ignition extension on the chamber comprising a metal frame of bars extending fore and aft of the extension; a refractory lining within the frame; a casing around the frame forming air passages between the casing and the refractory lining, said passages being separated by the bars and each passage having an air receiving inlet and an outlet discharging into the extension, the inlet and discharge being remote from each other and the passage conveying the air lengthwise of the extension from the inlet to the discharge.
5. In a furnace, the combination of a furnace chamber; an ignition extension on the chamber comprising a metal frame of bars extending fore and aft of the extension; a refractory lining within the frame; a casing around the frame forming air passages between the casing and refractory lining, said passages being separated by the bars, and each passage having an inlet at one end and a discharge to the extension at the opposite end and remote from the inlet; and means delivering fuel to the extension.
6. In a furnace, the combination of a furnace chamber; an ignition extension on the chamber comprising a metal frame of bars extending fore and aft of the extension; a refractory lining within the frame; a casing around the frame forming air passages between the casing and refractory lining, said passages being separated by the bars, and each passage having an inlet at the rear end

and discharging to the furnace extension at its front end and remote from the inlet; and means delivering fuel to the extension.

7. In a furnace, the combination of a furnace chamber; an ignition extension on the chamber comprising a metal frame of bars extending fore and aft of the extension; a refractory lining within the frame; a casing around the frame forming air passages between the casing and refractory lining, said passages being separated by the bars, inlets for said passages being formed through the casing, said passages conveying air axially along the extension and discharging to the furnace extension remote from the inlets; a valve ring rotatably mounted on the casing and adapted to adjust said inlet passages; and means delivering fuel to the extension.

8. In a furnace, the combination of a furnace chamber; an ignition extension on the chamber comprising a metal frame of bars extending fore and aft of the extension; a refractory lining made up of segmental refractories having their joints radially in line with the bars; a casing around the frame forming air passages between the casing and the refractory separated by the bars, each of said passages having an inlet at one end and a discharge to the extension at the opposite end remote from the inlet; and means delivering fuel to the extension.

In testimony whereof I have hereunto set my hand.
